(57) **CLAIM**

The ornamental design for a radio charger, as shown and described.

DESCRIPTION

FIG. 1 is a front perspective view of the radio charger of the present invention;

FIG. 2 is a rear perspective view;

FIG. 3 is a front view;

FIG. 4 is a rear view;

FIG. 5 is a top view;

FIG. 6 is a bottom view;

FIG. 7 is a left side view;

FIG. 8 is a right side view; and,

FIG. 9 is a front perspective view in an alternative position. The broken lines illustrating the hand drill in FIG. 3 are included for the purpose of illustrating environmental structure only and form no part of the claimed design. All other broken lines in the drawing figures are included for the purpose of illustrating portions of the charger that form no part of the claimed design.
